(57) **ABSTRACT**

A wearable climbing device, including a main body, including a bottom section to receive a foot of a user thereon, a top section removably connected to at least a portion of the bottom section, and a spike disposed on at least a portion of the bottom section to penetrate into at least one of a tree and a utility pole, a calf strap removably connected to at least a portion of the main body to be worn around a calf of the user, and an ankle strap removably connected to at least a portion of the main body to be worn around an ankle of the user.

6 Claims, 2 Drawing Sheets

FIG. 1

FIG. 2

1

WEARABLE CLIMBING DEVICE

BACKGROUND

1. Field

The present general inventive concept relates generally to climbing, and particularly, to a wearable climbing device.

2. Description of the Related Art

Climbing a tree and/or a utility pole can be a dangerous task. Regardless of the type of person performing the task, it remains difficult even for those doing it as a condition for commercial labor. Specifically, there is a substantial risk that a climber will fall and sustain severe injury while climbing the tree and/or the utility pole. Several factors contribute to the danger such as improper gear, improperly securing the gear, and/or mistakes during climbing.

Moreover, current equipment available in the market is known to cause pain and discomfort as these tools tend to employ single bar spurs. In other words, a majority of weight on the spur while climbing is favored by one side due to the single bar. In other words, the weight distribution on the spur is highly uneven.

Therefore, there is a need for a wearable climbing device that provides high stability for a user during climbing.

SUMMARY

The present general inventive concept provides a wearable climbing device.

Additional features and utilities of the present general inventive concept will be set forth in part in the description which follows and, in part, will be obvious from the description, or may be learned by practice of the general inventive concept.

The foregoing and/or other features and utilities of the present general inventive concept may be achieved by providing a wearable climbing device, including a main body, including a bottom section to receive a foot of a user thereon, a top section removably connected to at least a portion of the bottom section, and a spike disposed on at least a portion of the bottom section to penetrate into at least one of a tree and a utility pole, a calf strap removably connected to at least a portion of the main body to be worn around a calf of the user, and an ankle strap removably connected to at least a portion of the main body to be worn around an ankle of the user.

The bottom section may include a bottom first arm, and a bottom second arm disposed in parallel to the bottom first arm.

The main body may further include a stirrup disposed between the bottom first arm and the bottom second arm to receive at least a portion of the foot of the user thereon.

The top section may include a top first arm, and a top second arm disposed in parallel to the top first arm.

The spike may be bent in an angular direction away from the bottom section.

The main body may be adjustable in height by moving the top section toward or away from the bottom section.

The calf strap may include a plurality of layers.

The wearable climbing device may further include a plurality of bracing bands disposed on at least a portion of the main body to receive at least a portion of the calf strap therein and prevent the calf strap from lateral movement within each of the plurality of bracing bands.

2

The plurality of bracing bands may be removably connected to at least a portion of the top section.

BRIEF DESCRIPTION OF THE DRAWINGS

5

These and/or other features and utilities of the present generally inventive concept will become apparent and more readily appreciated from the following description of the embodiments, taken in conjunction with the accompanying drawings of which:

FIG. 1 illustrates a side perspective view of a wearable climbing device, according to an exemplary embodiment of the present general inventive concept; and

10

FIG. 2 illustrates a side perspective view of the wearable climbing device with a first section separated from a second section, according to an exemplary embodiment of the present general inventive concept.

DETAILED DESCRIPTION

20

Various example embodiments (a.k.a., exemplary embodiments) will now be described more fully with reference to the accompanying drawings in which some example embodiments are illustrated. In the figures, the thicknesses of lines, layers and/or regions may be exaggerated for clarity.

25

Accordingly, while example embodiments are capable of various modifications and alternative forms, embodiments thereof are shown by way of example in the figures and will herein be described in detail. It should be understood, however, that there is no intent to limit example embodiments to the particular forms disclosed, but on the contrary, example embodiments are to cover all modifications, equivalents, and alternatives falling within the scope of the disclosure. Like numbers refer to like/similar elements throughout the detailed description.

30

It is understood that when an element is referred to as being "connected" or "coupled" to another element, it can be directly connected or coupled to the other element or intervening elements may be present. In contrast, when an element is referred to as being "directly connected" or "directly coupled" to another element, there are no intervening elements present. Other words used to describe the relationship between elements should be interpreted in a like fashion (e.g., "between" versus "directly between," "adjacent" versus "directly adjacent," etc.).

35

The terminology used herein is for the purpose of describing particular embodiments only and is not intended to be limiting of example embodiments. As used herein, the singular forms "a," "an" and "the" are intended to include the plural forms as well, unless the context clearly indicates otherwise. It will be further understood that the terms "comprises," "comprising," "includes" and/or "including," when used herein, specify the presence of stated features, integers, steps, operations, elements and/or components, but do not preclude the presence or addition of one or more other features, integers, steps, operations, elements, components and/or groups thereof.

40

Unless otherwise defined, all terms (including technical and scientific terms) used herein have the same meaning as commonly understood by one of ordinary skill in the art to which example embodiments belong. It will be further understood that terms, e.g., those defined in commonly used dictionaries, should be interpreted as having a meaning that is consistent with their meaning in the context of the relevant art. However, should the present disclosure give a specific meaning to a term deviating from a meaning commonly

understood by one of ordinary skill, this meaning is to be taken into account in the specific context this definition is given herein.

LIST OF COMPONENTS

Wearable Climbing Device **100**
 Main Body **110**
 Bottom Section **111**
 Bottom First Arm **111a**
 Bottom Second Arm **111b**
 Top Section **112**
 Top First Arm **112a**
 Top Second Arm **112b**
 Spike **113**
 Stirrup **114**
 Fastener Receiving Apertures **115**
 Calf Strap **120**
 Bracing Bands **130**
 Ankle Strap **140**
 Strap Body **141**
 Buckle **142**
 Strap Holder **143**
 Connecting Ring **150**
 Rod Fasteners **160**
 Fastener Receiving Connectors **170**

FIG. 1 illustrates a side perspective view of a wearable climbing device **100**, according to an exemplary embodiment of the present general inventive concept.

FIG. 2 illustrates a side perspective view of the wearable climbing device **100** with a first section **111** separated from a second section **112**, according to an exemplary embodiment of the present general inventive concept.

The wearable climbing device **100** may be constructed from at least one of metal, plastic, cloth, wood, and rubber, etc., but is not limited thereto.

The wearable climbing device **100** may include a main body **110**, a calf strap **120**, a plurality of bracing bands **130**, an ankle strap **140**, a connecting ring **150**, a plurality of rod fasteners **160**, and a fastener receiving connectors **170**, but is not limited thereto.

Referring to FIGS. 1 and 2, the main body **110** is illustrated as a plurality of rods (e.g., two rods). However, the main body **110** may be a single rod and/or more than two rods (e.g., three, four, five, six, etc.).

The main body **110** may include a bottom section **111**, a top section **112**, a spike **113**, a stirrup **114**, and a plurality of fastener receiving apertures **115**, but is not limited thereto.

The bottom section **111** may include a bottom first arm **111a** and a bottom second arm **111b**, but is not limited thereto.

The bottom first arm **111a** may be disposed in parallel to the bottom second arm **111b**. Moreover, the bottom second arm **111b** may be distanced away from the bottom first arm **111a**. Also, the bottom first arm **111a** may have a size and/or a shape equivalent to a size and/or a shape of the bottom second arm **111b**.

The top section **112** may include a top first arm **112a** and a top second arm **112b**, but is not limited thereto.

The top first arm **112a** may be disposed in parallel to the top second arm **112b**. Moreover, the top second arm **112b** may be distanced away from the top first arm **112a**. Also, the top first arm **112a** may have a size and/or a shape equivalent to a size and/or a shape of the top second arm **112b**.

Furthermore, the top section **112** may be removably connected at a first end to at least a portion of a first end of the bottom section **111**. More specifically, the top first arm

112a and/or the top second arm **112b** may be removably connected to at least a portion of the bottom first arm **111a** and/or the bottom second arm **111b**, respectively. Collectively, the bottom first arm **111a** and/or the top first arm **112a** may be considered a first arm of the main body **110**, and the bottom second arm **111b** and/or the top second arm **112b** may be considered a second arm of the main body **110**.

The spike **113** may be disposed on at least a portion of a second end of the bottom section **111** opposite with respect to the first end. Additionally, referring again to FIGS. 1 and 2, the spike **113** is illustrated to extend away from the bottom first arm **111a**. However, the spike **113** may extend away from the bottom second arm **111b**. The spike **113** may taper from the second end of the bottom section **111** to a point at a distance away from the bottom section **111**. Accordingly, the spike **113** may be inserted and/or penetrate into a portion of a tree and/or a utility pole. The spike **113** may support the main body **110** thereon, while inserted within the tree and/or the utility pole. Furthermore, the spike **113** may be bent in an angular direction away from the bottom section **111**. It is important to note that the spike **113** may be bent away from the bottom section **111** because it would be difficult to insert the spike **113** into the tree and/or the utility pole from under the bottom section **111**.

The stirrup **114** may be disposed between the bottom first arm **111a** and/or the bottom second arm **111b**. In other words, the stirrup **114** may connect the bottom first arm **111a** to the bottom second arm **111b**. Furthermore, the stirrup **114** may receive at least a portion of a foot of a user thereon, such that the user may stand on the stirrup **114**.

The plurality of fastener receiving apertures **115** may be disposed on at least a portion of the bottom first arm **111a**, the bottom second arm **111b**, the top first arm **112a**, and/or the top second arm **112b**. The plurality of fastener receiving apertures **115** may receive at least one fastener therein.

The calf strap **120** may include a plurality of layers and a fastener (e.g., a hook and loop fastener), but is not limited thereto.

The calf strap **120** may be removably connected to at least a portion of the main body **110**. More specifically, the calf strap **120** may wrapped in a loop around at least a portion of a second end of the top section **112**, such that the calf strap **120** may wrap around the top first arm **112a** and/or the top second arm **112b**. The calf strap **120** may be disposed (i.e., worn) around a calf of the user to secure the calf of the user against the top first arm **112a** and/or the top second arm **112b**. The calf strap **120** may be adjusted with respect to size (i.e., diameter, circumference) to fit around the calf of the user.

The calf strap **120** may have a first layer (i.e., an inner layer) constructed of synthetic fabric and is highly resistant to wear and tear. The calf strap **120** may have a second layer (i.e., a middle layer) constructed of foam to absorb an impact from an external object, such as the tree and/or the utility pole. The calf strap **120** may have a third layer (i.e., an outer layer) constructed of foam, different from the second layer, to absorb the impact from the external object, as well as, reduce a temperature level within the calf strap **120**.

The plurality of bracing bands **130** may be disposed on at least a portion of the main body **110** and removably connected to at least a portion of the calf strap **120**. More specifically, each of the plurality of bracing bands **130** may receive at least a portion of the calf strap **120** therein. Each of the plurality of bracing bands **130** may be removably connected to at least a portion of the second end of the top first arm **112a** and/or the top second arm **112b**. The plurality of bracing bands **130** may prevent the calf strap **120** from

lateral movement within each of the plurality of bracing bands **130** absent an application of force (e.g., pushing, pulling) from the user, such that the calf strap **120** remains in a fixed position while worn around the calf of the user.

The ankle strap **140** may include a strap body **141**, a buckle **142**, and a strap holder **143**, but is not limited thereto.

The strap body **141** may be connected to at least a portion of the bottom section **111**. Referring again to FIGS. 1 and 2, the strap body **141** is illustrated to be connected to the bottom second arm **111b**. However, the strap body **141** may be removably connected to at least a portion of the bottom first arm **111a**. The strap body **141** may be disposed (i.e., worn) around an ankle of the user to secure the ankle of the user against the bottom first arm **111a** and/or the bottom second arm **111b**. The strap body **141** may be adjusted with respect to size (i.e., diameter, circumference) to fit around the ankle of the user.

The buckle **142** may be disposed on at least a portion of a first end of the strap body **141**. The buckle **142** may receive a second end of the strap body **141** to fasten at least a portion of the second end of the strap body **141** therein. In other words, the second end of the strap body **141** may be inserted through the buckle **142** to fasten the second end of the strap body **141** into the buckle **142**.

The strap holder **143** may be movably (i.e., slidably) connected to at least a portion of the strap body **141**. The strap holder **143** may move toward the first end of the strap body **141** in a first direction, and toward the second end of the main body **141** in a second direction. The strap holder **143** may cover at least a portion of the second end of the strap body **141**, while the second end of the strap body **141** is inserted into the buckle **142**. As such, the strap holder **143** may prevent the second end of the strap body **141** from moving away from a center portion of the strap body **141**.

The connecting ring **150** may be connected to at least a portion of the bottom section **111**. Referring again to FIGS. 1 and 2, the connecting ring **150** is illustrated to be connected to the bottom second arm **111b**. However, the connecting ring **150** may be connected to at least a portion of the bottom first arm **111a**.

The connecting ring **150** may connect the ankle strap **140** to the bottom section **111**.

Each of the plurality of rod fasteners **160** may include a screw, a nail, a bolt, a magnet, and/or any combination thereof, but is not limited thereto.

Each of the plurality of rod fasteners **160** may be removably connected (i.e., inserted) within at least one of the plurality of fastener receiving apertures **115**.

Each of the plurality of fastener receiving connectors **170** may include a washer, a nut, a magnet, and/or any combination thereof, but is not limited thereto.

Each of the plurality of fastener receiving connectors **170** may removably connect to at least one of the plurality of rod fasteners **160**. During use, the plurality of rod fasteners **160** may removably connect through the plurality of fastener receiving apertures **115** to the plurality of fastener receiving connectors **170** to secure the top section **112** to the bottom section **111**, such that the top section **112** may be prevented from moving off the bottom section **111**. Accordingly, the top section **112** may be adjusted (i.e., toward or away from) with respect to the bottom section **111** to adjust a height of the main body **110** based on a length of a leg of the user.

Therefore, the wearable climbing device **100** may provide stability for the user while climbing due to having the first arm and the second arm of the main body **110**. Additionally,

the calf strap **120** and/or the ankle strap **140** connect around different portions of the leg of the user to support the user and remain steady.

The present general inventive concept may include a wearable climbing device **100**, including a main body **110**, including a bottom section **111** to receive a foot of a user thereon, a top section **112** removably connected to at least a portion of the bottom section **111**, and a spike **113** disposed on at least a portion of the bottom section **111** to penetrate into at least one of a tree and a utility pole, a calf strap **120** removably connected to at least a portion of the main body **110** to be worn around a calf of the user, and an ankle strap **140** removably connected to at least a portion of the main body **110** to be worn around an ankle of the user.

The bottom section **111** may include a bottom first arm **111a**, and a bottom second arm **111b** disposed in parallel to the bottom first arm **111a**.

The main body **110** may further include a stirrup **114** disposed between the bottom first arm **111a** and the bottom second arm **111b** to receive at least a portion of the foot of the user thereon.

The top section **112** may include a top first arm **112a**, and a top second arm **112b** disposed in parallel to the top first arm **112a**.

The spike **113** may be bent in an angular direction away from the bottom section **111**.

The main body **110** may be adjustable in height by moving the top section **112** toward or away from the bottom section **111**.

The calf strap **120** may include a plurality of layers.

The wearable climbing device **100** may further include a plurality of bracing bands **130** disposed on at least a portion of the main body **110** to receive at least a portion of the calf strap **120** therein and prevent the calf strap **120** from lateral movement within each of the plurality of bracing bands **130**.

The plurality of bracing bands **130** may be removably connected to at least a portion of the top section **112**.

Although a few embodiments of the present general inventive concept have been shown and described, it will be appreciated by those skilled in the art that changes may be made in these embodiments without departing from the principles and spirit of the general inventive concept, the scope of which is defined in the appended claims and their equivalents.

The invention claimed is:

1. A wearable climbing device, comprising:
a main body, comprising:

a bottom section to receive a foot of a user thereon, the bottom section comprising:
a bottom first arm, and

a bottom second arm disposed in parallel to the bottom first arm,

a top section movably and removably connected to at least a portion of the bottom section, the top section comprising:

a top first arm disposed in line with and parallel to the bottom first arm such that the top first arm is movably and removably connected to the bottom first arm, and

a top second arm disposed parallel to the top first arm, such that the top second arm is disposed in line with and parallel to the bottom second arm such that the top second arm is movably and removably connected to the bottom second arm to allow the main body to be adjustable in height by

moving the top section toward or away from the bottom section, and

- a spike disposed on at least a portion of the bottom section to penetrate into at least one of a tree and a utility pole;
- a calf strap removably connected to at least a portion of the main body to be worn around a calf of the user; and
- an ankle strap removably connected to at least a portion of the main body to be worn around an ankle of the user.
2. The wearable climbing device of claim 1, wherein the main body further comprises:
- 10 a stirrup disposed between the bottom first arm and the bottom second arm to receive at least a portion of the foot of the user thereon.
3. The wearable climbing device of claim 1, wherein the spike is bent in an angular direction away from the bottom section.
4. The wearable climbing device of claim 1, wherein the calf strap comprises a plurality of layers.
5. The wearable climbing device of claim 1, further comprising:
- 20 a plurality of bracing bands disposed on at least a portion of the main body to receive at least a portion of the calf strap therein and prevent the calf strap from lateral movement within each of the plurality of bracing bands.
- 25 6. The wearable climbing device of claim 5, wherein the plurality of bracing bands are removably connected to at least a portion of the top section.
